Filed Mar. 12, 1969, Ser. No. 16,205

Term of patent 14 years

Int. Cl. D26—02

U.S. Cl. D48—23

FIG. 1

FIG. 2

FIG. 3

FIG. 1 is a perspective view from the bottom and one corner of the fixture embodying my invention;

FIG. 2 is a perspective view from the bottom and opposite corner of such fixture; and

FIG. 3 is a bottom view of the fixture.

The criss-cross hatching at one side of the bottom of the fixture indicates an air vent.

The raised panels on the sides of the fixture have a wood grain appearance.

I claim:

The ornamental design for a surface mounted light fixture, substantially as shown and described.
